GARBAGE CAN

Paul C. Gunn, Fort Worth, Tex., assignor to Loma Plastics, Inc., Fort Worth, Tex., a corporation of Texas

Application September 12, 1956, Serial No. 42,908

Term of patent 14 years

(Cl. D58—17)

Fig. 1

Des. 180,187

PAGE 2

Fig. 2

Fig. 3

Fig. 4

Figure 1 is a side elevational view of a garbage can showing my new design;

Figure 2 is a top plan view thereof;

Figure 3 is an enlarged fragmentary cross-sectional view thereof, taken along the line 3—3 of Figure 1; and

Figure 4 is a perspective view thereof.

The sides not shown are the same as the side shown.

I claim:

The ornamental design for a garbage can, as shown and described.
